UNITED STATES PATENT OFFICE.

BYRON PHELPS, OF SEATTLE, WASHINGTON.

LOCK.

SPECIFICATION forming part of Letters Patent No. 774,970, dated November 15, 1904.

Application filed December 4, 1903. Serial No. 183,820. (No model.)

To all whom it may concern:

Be it known that I, BYRON PHELPS, a citizen of the United States, residing at Seattle, King county, Washington, have invented certain new and useful Improvements in Locks, of which the following is a full, clear, and exact description.

My invention relates to locks and latches, and particularly to that type of a lock known as a "unit" lock, in which all of the parts are assembled before the lock is applied to the door.

Among the objects of this invention are to provide certain new, economical, and effective features of construction, hereinafter more fully set forth. Incidentally the construction is such that I am enabled to employ sheet or wrought metal in forming nearly the entire mechanism. In the past it has been common to construct many of the parts of castings. By my invention this is avoided, and I attain certain economies of construction heretofore impossible.

Other objects and advantages will be apparent from a reading of the following description.

In the drawings, Figure 1 is a plan view of my improved lock, showing a portion of a door at the rear thereof. Fig. 2 is a side elevation of the parts shown in Fig. 1, said view being taken partly in section and one of the side plates being removed. Fig. 3 is a vertical section of the lock, some of the parts being shown in elevation, said section being coincident with the axis of the knob-spindle. Fig. 4 is a cross-section of the knob-spindle, showing the roll-backs and a portion of the latch-slide in side elevation, the latch-slide being retracted by rotation of the knob-spindle. Fig. 5 is a side elevation of a roll-back for the knob-spindle. Fig. 6 is a side elevation of a roll-back for the key-spindle. Fig. 7 is a view similar to Fig. 4, the roll-backs being shown in different position, the latch-slide being retracted by the key-spindle. Fig. 8 is a side view of the supporting barrel or hub detached and a portion of the side plate. Fig. 9 is a longitudinal sectional view of the knob-spindle with one of the knobs attached thereto and showing a night-latch and key-controlled operating

mechanism in side elevation. Fig. 10 is a view of the inside of the outer section of the outer knob, showing a cylinder-lock in end elevation. Fig. 11 is an end elevation of the parts shown in Fig. 9 looking from left to right. Fig. 12 is a sectional view of the night-latch-controlling member. Fig. 13 is an end view of the same. Fig. 14 is a section on the plane of the line *a a*, Fig. 9, showing the night-latch and controlling member in elevation, the night-latch being in the "on" position. Fig. 15 is a similar view, the position of the night-latch and controlling member being shifted to show the night-latch in the "off" position.

1 is a portion of a door which, in accordance with practice, has a notch cut in the stile thereof to receive the lock.

2 and 3 are side plates, which may, if desired, constitute escutcheon-plates, but whose main function is to support and hold the latch mechanism in place. If desired, escutcheon-plates 4 5 may be separately formed and secured to the side plates 2 3. In practice the plates 2 3 may be formed of sheet metal. By this arrangement it is possible to make the side plates 2 3 of conventional form best adapted to the mechanical purpose for which they are intended, whereas the escutcheon-plates 4 5 may be first given any desired design or ornamentation and then secured in any well-known manner to the plates 2 3. The plate 3 in the particular form shown constitutes a part of the latch-carrying frame, and one end may be bent up to form the face-plate 6.

7 is a latch bolt or head, which may operate through a perforation or recess in the face-plate 6. Between the plates 2 and 3 may be located a third plate 8, one end of which may be bent up and secured to the plate 3, as at 81, so that it, together with plate 3, will constitute said latch-carrying frame. The other end of plate 8 may be also bent up and connected with the face-plate 6, as at 82, to reinforce the same. The plate 8 may be formed of sheet metal. This plate is so shaped that a space is formed between the plates 3 and 8, in which the latch mechanism proper is located.

9 is a latch-slide, one end of which is bifurcated and hooked at 91 or otherwise suitably formed to be engaged by the roll-backs 10 11. The other end of the latch-slide 9 is secured to the latch bolt or head 7—for example, by means of a hooked portion 92 engaging with the pin 71 on the said latch-bolt 7.

93 is a perforated bearing carried by the latch-slide 9, through which bearing may pass the stem 72 of the latch bolt or head 7. Thus the latch-bolt 7 may be guided partly by the side plates and partly by the bearing 93.

12 is an "easy spring," which may surround the stem 72 and one end of which may bear against the latch-bolt 7, while the other end may take up against the bearing 93.

13 is a second spring, which may bear one end against the bearing 93 and the other end against a stationary tubular barrel-bearing 14, which constitutes the bearing-support for the knob-spindle 15. To steady that end of the spring against the barrel 14, I may provide a stud 141, with which the spring 13 may engage. The barrel 14 is secured to the frame-plates 3 and 8 and has a recess or perforations therein in which are located the roll-backs 10 11, the recesses or perforations being of such size as to permit the rocking of said roll-backs. The roll-back 11 is carried by the knob-spindle 15, which spindle is tubular in form. This knob-spindle 15 is also recessed or perforated to allow the introduction of said roll-backs, and said recesses or perforations are in the particular form shown formed so that said roll-back 11 is when the parts are assembled held in such relation to the knob-spindle 15 that it always turns therewith and cannot rotate independently thereof. This end is accomplished by forming notches 151 (see Fig. 9) at the end of the recess or perforations in said knob-spindle, said notches being of a suitable width to receive the shank or body portion of the roll-back 11. The perforations or recesses in said knob-spindle 15 are of such shape as to permit the other roll-back, 10, to be rocked independently of said knob-spindle by the action of a separate key-controlled spindle 16, so that by this means the bolt 7 may be retracted if the knob-spindle should be locked. In the outer knob is carried a cylinder-lock 17, arranged to receive a key 18. 172 is an offset on the case 17 to prevent said lock from rotating in said knob. The roll-back 10 has an angular opening to receive said key-controlled spindle 16, while the other roll-back, 11, may have a round opening of such a size as to permit the key-controlled spindle 16 to pass freely therethrough and be rotated independently thereof. The outer knob is preferably formed of two shells or sections which are held together by screws 19 19, which screws may pass through holes in the inner section and engage with screw-threaded bosses 20 20 on the inner side of the outer shell. In the preferred con-

struction these two knob-sections comprise the two shells 21 22, which latter are reinforced on the inside for the purpose partly of strengthening the knob, partly to afford secure support for the screws 19 and bosses 20, 70

and partly to form bearings for the cylinder-lock 17. This reinforcement is effected by plates 211 222, which are best seen in Fig. 9. Within these reinforcing-plates 211 222 two opposite annular shoulders are formed of a 75 suitable size to receive and center the cylinder 17. The inner knob-section 21, together with its reinforcing-plate 211, is held in fixed engagement with the tubular knob-spindle 15, while the inner edge of the reinforcing-plate 80 222 is preferably spun outwardly and around the edge of the opening in the outer section 22. This affords one means to securely clamp said section and reinforcing-plate together and incidentally form a smooth passage or 85 bearing for the hub 171 of said lock.

23 is an annular covering-plate which overlies and hides the screw-heads 19 19 when the parts are assembled. The inner edge of the said plate 23 surrounds the knob-spindle and 90 bears against the end of the barrel 14 and so as to be held in place thereby. The night-latch comprises means for locking the tubular knob-spindle 15 against rotation in the stationary bearing 14. The night-latch comprises a dog 95 24, pivoted in the tubular spindle 15. 241 is a locking-nose on said dog 24, which is arranged to project outwardly to engage with a notch 142 in the barrel 14. (See Figs. 3 and 8.) This locking-nose 241 is or may be 100 pressed outwardly by means of a spring 242.

243 is a night-latch-controlling member, which may be a ring having a cam or cam-surfaces 244 therein, which overstand the end of the locking-dog 24. When the controlling 105 member 243 is turned so that the low part of one of the cam-surfaces 244 rests above the end of the dog 24, the locking-nose 241 will project outwardly and engage in the aforementioned notch 142 in the non-rotatable bearing 14. Inasmuch as the nose or end of the dog 24 likewise passes through a suitable perforation or slot in the knob-spindle 15 it will be seen that when the dog engages with the stationary barrel the knob-spindle will be locked against 115 rotation. When, however, the controlling member 243 has been turned to the proper degree, so that a high part of one of the cam-surfaces 244 will stand over the end of the locking-dog, the latter will be depressed, so 120 that its locking-nose 241 will be freed from the stationary barrel 14. When the dog is in this position, the knob-spindle is free to turn. The controlling member 243 is loosely mounted on the knob-spindle. For convenience 125 sake a notch may be formed in each of the cam-surfaces 244 at the position wherein the dog 24 is freed from the barrel 14. This notch serves to receive the edge of the dog 24. The latter being spring-pressed holds the con- 130

trolling device 243 from becoming accidentally shifted.

25 is the inside knob, which may be suitably secured to the inner end of the knob-spindle 15—for example, by means of a pin 251.

26 is a bridging member which may span the space between the plates 3 and 8 and is secured thereto. The function of the bridging member 26 is to reinforce the said plates 3 and 8. One end of the bridging member 26 may be offset, as at 261. In Fig. 1 a portion of said bridge is broken away to show said offset. This offset portion, together with 15 the plate 8, forms a double thickness of metal, which may be perforated and tapped to receive the threaded end of an adjusting-screw 27, by means of which the side plates 2 and 3 may be drawn toward each other and clamped 20 firmly against the sides of the door 1 when the lock is in place.

From the foregoing it will be seen that by far the majority of the parts may be formed of wrought or sheet metal. The various 25 plates may be riveted or otherwise fastened together. Many of the parts may be connected integrally. The stud 141 may have a recess therein, as indicated in Fig. 2, to provide clearance for the end of the stem 72 of the 30 latch bolt or head. This stud may be riveted to the tubular bearing 14. The perforated bearing 93, carried by the latch-slide, receives the thrust of the heavy knob-spring 13 as well as the thrust of the easy spring 12. Inasmuch as the escutcheon-plates 4 & 5 may be formed from sheet metal and in any suitable design and inasmuch as the said escutcheon-plates 4 & 5 are reinforced by said side plates 2 & 3, the former may be made of very light material, resulting in great economy.

In operation to prevent the latch-bolt from being operated by the knobs the user turns the controlling device 243 so that the dog 24 engages with the stationary barrel-bearing 14, whereupon the tubular knob-spindle 15 is locked therewith and neither knob can be turned. The latch-bolt may, however, be retracted by means of a key 18, which may be inside in the cylinder-lock 17, which key when 45 turned rotates the spindle 16, and thereby the roll-back 10, which in turn engages the latch-slide 10, retracting the same and incidentally the latch-bolt 7.

What I claim is—

55 1. In a lock in combination, latch mechanism embracing a latch bolt or head, a rotatable knob-spindle, bolt-actuating means connected with said spindle and adapted to be operated to retract said bolt by the rotation 60 of said spindle, mechanism embracing a tilting dog located within said spindle and arranged to move outwardly through the side of the same to lock said spindle from rotation, a pivot within said spindle for said dog, means 65 on one side of the lock to control said dog

and key-operated means on the other side of said lock to move said latch bolt or head independently of the locked spindle.

2. In a lock in combination, latch mechanism embracing a latch bolt or head, a rotatable knob-spindle, bolt-actuating means connected with said spindle and adapted to be operated to retract said bolt by the rotation of said spindle, mechanism embracing a tilting dog located within said spindle and arranged to move outwardly through the side of the same to lock said spindle from rotation, a pivot inside said spindle for said dog, means on one side of the lock to control said dog and key-operated means on the other side of 80 said lock to move said latch bolt or head independently of the locked spindle.

3. In a lock in combination, latch mechanism embracing a latch bolt or head, a rotatable knob-spindle, bolt-actuating means connected with said spindle and adapted to be operated to retract said bolt by the rotation of said spindle, mechanism embracing a pivoted spring-pressed dog located within said spindle and arranged to move outwardly 90 through the side of the same to lock said spindle from rotation, a pivot and spring for said dog said pivot and spring being located within said spindle, means on one side of the lock to control said dog and key-operated means 95 on the other side of said lock to move said latch bolt or head independently of the locked spindle.

4. In a lock in combination, a continuous tubular bearing, a continuous tubular knob-spindle supported within the same, a knob at each end thereof, a latch bolt or head, a latch-slide connected therewith, latch-operating mechanism carried by said knob-spindle, recesses in said knob-spindle and said tubular bearing to receive said latch-operating mechanism, a latch-slide connected with said latch bolt or head and said latch-operating mechanism, said latch-bolt having a sliding engagement relatively to said slide, substantially as 110 described.

5. In a lock in combination, a continuous tubular bearing, a continuous tubular knob-spindle supported within the same, a knob at each end thereof, a latch bolt or head, a latch-slide connected therewith, latch-operating mechanism carried by said knob-spindle, recesses in said knob-spindle and said tubular bearing to receive said latch-operating mechanism, a latch-slide connected with said latch bolt or head and said latch-operating mechanism, said latch-bolt having a sliding engagement relatively to said slide, means for locking together said tubular bearing and said tubular knob-spindle, and key-controlled 125 means for operating said latch bolt or head independently of the knob-spindle.

6. In a lock adapted to be inserted in a notch in the stile of a door, a wrought-metal frame comprising a side plate bent at an angle at

one end to form a face-plate, a second wrought-metal plate spaced apart therefrom, one end of said second plate being secured to the said side plate, the opposite end of said second plate being offset and bearing against the inside of the end plate to reinforce and strengthen the same.

7. In a lock adapted to be inserted in a notch in the stile of a door, a wrought-metal frame comprising a side plate bent at an angle at one end to form a face-plate, a second wrought-metal plate spaced apart therefrom, one end of said second plate being secured to the said side plate, the opposite end of said second plate being offset and bearing against the inside of the end plate to reinforce and strengthen the same, and a bridging-plate extending across from the side plate to said second plate and being bent to reinforce said second plate, a screw-passage in the reinforced part of said second plate to receive an adjusting-screw.

8. In a lock adapted to be inserted in a notch in the stile of a door, a wrought-metal frame comprising a side plate bent at an angle at one end to form a face-plate, a second wrought-metal plate spaced apart therefrom, one end of said second plate being secured to the said side plate, the opposite end of said second plate being offset and bearing against the inside of the end plate to reinforce and strengthen the same, and a bridging-plate extending across from the side plate to said second plate and being bent to reinforce said second plate, a screw-passage in the reinforced part of said second plate to receive an adjusting-screw, a second side plate and an adjusting-screw to connect the same to said second plate.

40 9. In a lock adapted to be inserted in a notch in the stile of a door, two side plates, an end plate attached to one of said side plates, said side plates being constructed to form bearings for separate escutcheon-plates.

45 10. In a lock adapted to be inserted in a notch in the stile of a door, two side plates, an end plate attached to one of said side plates, said side plates being constructed to form bearings for separate escutcheon-plates, and separate escutcheon-plates attached to said side plates.

50 11. In a lock adapted to be inserted in a notch in the stile of a door, a wrought-metal frame comprising a side plate and a second plate secured together toward their ends, said side plate being bent to form an end plate to overlap the edge of a door, said second plate being secured to the side plate to reinforce the end plate, a space between said side plate and

second plate, a slide mounted in said space, a latch-bolt, and latch-operating mechanism. 60

12. In a lock adapted to be inserted in a notch in the stile of a door in combination, a frame including a side plate and a second plate secured thereto but spaced apart therefrom to form a space for the latch mechanism, latch 65 mechanism embracing a latch-slide, a latch-bolt carried thereby but longitudinally movable independently thereof, a bearing on said slide to guide said bolt, separate springs located on opposite sides of said bearing, one of 70 said springs coacting with the bolt directly, the other of said springs operating the bolt indirectly through the medium of the slide.

13. In a lock adapted to be inserted in a notch in the stile of a door in combination, a frame 75 comprising a plate arranged to rest against the side of the door and overlap the edge thereof, and a second plate secured thereto but spaced apart therefrom to form a space for the latch mechanism, said latch mechanism including a 80 slide guided by one of said plates and a reciprocating bolt guided partially by said slide and partially by said plates, said bolt being fitted to the space between said plates, and latch-operating mechanism coacting with said slide 85 to retract and advance said bolt.

14. In a lock, a knob formed of two separable shells, means for securing them together sheet-metal reinforcing-plates within said shells, a cylinder-lock arranged to be held 90 within said shells when the same are assembled, said reinforcing-plates being shaped to receive, support and center said cylinder-lock.

15. In a lock, a knob, a shank projecting 95 from one end of said knob, said knob being formed of separable sections, a reinforcing-plate for the section secured to the knob-shank, the means of securing said section to said knob-shank also serving to secure said reinforcing-plate in place, the reinforcing-plate for the other section being located within said last-mentioned section and secured thereto by a flange projecting through a central opening in said last-mentioned section 100 and flanged outwardly over the outer surface of said last-mentioned section, and means for securing said two reinforcing-sections together. 105

Signed at New York, N. Y., this 3d day of December, 1903.

BYRON PHELPS.
